Claims priority, application Germany July 3, 1958

8 Claims. (Cl. 289—2)

My invention relates to a yarn-knotting device for use in textile manufacture, and more particularly to a device for forming a fisherman's knot to join yarn ends.

It is known to provide such a knotting device with two tie beaks which operate to form a fisherman's knot. In a knot of this type, each of the two yarn ends to be tied together is first given a simple individual knot through whose loop the other yarn end can glide. Since each yarn end has its own knot, the two knots can move toward each other during tightening of the loops until they touch each other and then prevent each other from gliding out of the loop of the adjacent yarn end. In known knotting devices for forming such a fisherman's knot, a tensioning of the tie is effected after forming and looping the individual knots. The tensioning of the tie takes place before the two yarn ends are removed from the tie beaks of the knotting device. This imposes a great stress along the entire yarn end portions not only between the knot being formed and the tie beaks but also between the length of yarn located between the knot and the yarn coil from which the yarn end is taken. Such stress may result in weakening or breaking the yarn at an undesired location, if the tie beaks hold the yarn ends firm enough and the tensioning member of the knotter is being driven.

It is therefore an object of my invention to devise a knotter of the above-mentioned type that obviates the danger of overstress.

It is another object of my invention to provide a device for knotting yarn ends which does not impose an excessive stress on the yarn which might otherwise rupture the yarn.

It is a further object of the invention to provide means for knotting and simultaneously testing the knotted portion of yarn for sufficient tensile strength.

Another object of the invention is to provide a device for forming a fisherman's knot wherein the loosening or releasing of the yarn ends by the device is effective only after the looping and closing of the individual knots on each yarn end portion, but prior to the pulling of the individual knots together.

To these ends, and in accordance with my invention, the knotting device is so designed that the tie beaks loosen or release the yarn ends seized thereby at a moment where the individual knots at the end of the respective yarn ends are looped and closed, and that only thereafter does the tensioning and tightening of the yarn tie commence by pulling the individual knots toward each other. Such a knotter affords the assurance of reliably avoiding the occurrence of excessive strain in the yarn or the yarn ends, thus preventing weakening or breaking in the yarn lengths to be tied together.

According to another feature of my invention, after releasing the yarn ends, hence after the forming of the individual knots at the tips of the respective yarn ends, the tie beaks are caused to perform the return motion in opposite direction from the forward motion previously effective when looping the knots. Such a design simplifies the construction of the knotting device.

2

It is further preferable, according to another feature of my invention, to sever any protruding portions of the yarn end at a moment not later than the instant that the yarn ends are released from the tie beaks. If desired, the severing operation may coincide simultaneously with the release of the yarn ends in such a manner that the severing causes the instantaneous release of the yarn end of the just-knotted yarn portion. However, it is also possible to open the tie beaks after completing the looping and closing of the knot, so that the yarn ends can run out of the beaks.

The foregoing and more specific objects and features of my invention will be apparent from the embodiment shown by way of example on the accompanying drawings, in which:

Figs. 1 through 9 illustrate schematically respectively different stages of the knotting operation according to the invention.

Figs. 10 and 11 are partly sectional top views of the knotting device with the knot-forming components shown in respectively different positions.

Figs. 12 and 13 show details of the knotter for the purpose of illustrating the yarn path through the knotter.

Fig. 14 is a cross-sectional view of the knotter; and Fig. 15 is an explanatory graph relating the knotting performance.

Rotatably mounted in a cylindrical portion of the knotter housing 1 is a cup-shaped disc 3 (Figs. 14, 10, 11), which has a hollow shaft 21 (Fig. 14) driven through a pair of angularly related spur gears 22, 23, of which the gear 23 is essentially a segment biased clockwise about its shaft 23a by means of a spring 19. The segment gear 23 is joined with a follower arm 25 resting against the periphery of a driving cam 24 mounted on a shaft 29 which is driven from a motor (not shown) to perform a single, full-turn rotation whenever the knotter is to enter into operation. Such single revolution may be accomplished by having connected between the motor and shaft 29 a single-revolution clutch such as that illustrated at page 161 of "Mechanism" by Joseph S. Beggs, McGraw-Hill, 1955. The upper rim of the cup disc 3 is provided on part of its periphery with a toothed gear portion 4 (Figs. 14, 10, 11) which is in meshing engagement with driving pinions 5 and 5a joined to respective tie beaks 26 and 27 for rotating and operating them. The beak members 26, 27 are provided with cheek members 50 and jaw members 51 pivoted at 52 (Figs. 4, 9). The jaw members 51 are activated to swing about their respective pivots 52 when they are contacted by eccentric cylindrical walls 53 (Fig. 10) of the respective housings 26a, 27a of beaks 26, 27. The cup disc 3 is further provided with slots 6, 7 (Fig. 11) which extend from the cup rim to the slot bottom, the respective slot bottoms having different depths and serving for receiving the yarn ends to be tied together.

Mounted outside of the cup disc 3 and concentrically thereto are stationary sheet-metal members 8 which are likewise provided with yarn-receiving slots 9 and 10 whose slot bottoms are likewise spaced from the cup rim respectively different amounts (Figs. 10 to 13). Mounted on the periphery of the circular housing portion 1 are two yarn clamps, each of which comprise a fixed pin 11 and a movable clamping member 12. Each clamping member 12 forms one arm of a lever 14 rotatable about a fixed pivot pin 13. The other end of each lever 14 is engageable with one of two slots 15 in the cylindrical wall of the cup disc 3. The levers 14 (Fig. 10) are biased at their pivots 13 to urge their ends 14 toward and into slots 15 and also urge clamps 12 away from pins 11. However, when slots 15 rotate out of the range of ends 14, the opposite ends 12 become pressed against their respective pins 11 to clamp the yarn.

Located between the two tie beaks 26 and 27 is a forked tensioning member 17 having fork branches 17a and 17b (Figs. 14, 6-11). The tensioning member 17 is axially displaceable and can be shifted into a position where the ends of fork branches 17a and 17b protrude toward the left (Fig. 14) beyond the location of the tie beaks.

The tensioning member 17 is driven by means of a lever 28 (Fig. 14) pivoted at 28a and controlled by another cam 30 fixedly mounted on the cam shaft 29. The tensioning member 17 is biased toward the right by means of a helical spring 31 positioned around the shaft and axially biased between pin 31a, fixed to the shaft of member 17, and abutment 31b in hollow shaft 21, thus urging member 17 to normally occupy the position shown in Fig. 14. The lever 28 engages the cam 30 through a cam follower provided with an adjustable set screw 41 which can be arrested in the proper desired position within a sleeve 43 by means of an adjustable collar or lock nut 42. The sleeve 43 is displaceably mounted in the lower end of the lever 28 and transmits its cam-follower motion through a helical compression spring 44 on to the lever 28 in whose bore 45 the sleeve 43 can freely glide during compression of the spring 44.

The yarn knotting operation takes place as follows.

The end portions *a* and *b* of the two yarn lengths to be tied together are first so positioned in readiness that the ends *c* and *d* point in different directions (Fig. 1). This may be accomplished by seizing and positioning devices operating, for example, by suction and which are well known in the art of textile winding machines. The yarn pieces *a* and *b* pass into the bight of the adjacent beaks 26 and 27 respectively. Now the cam shaft 29 (Fig. 14) is driven to perform one full revolution. The cam 24 fixed to shaft 29, acting through follower 25 and gears 23, 22, drives the cup disc 3 in mesh with the pinions 5 and 5a, so that the tie beaks 26 and 27 perform mutually opposed rotations, thus reaching the respective positions illustrated in Fig. 2. During continued rotation the beaks 26, 27 pass into the position of Fig. 3 and form a loop in each yarn portion *a*, *b*. During further rotation of the tie beaks, the terminal ends *c* and *d* of respective yarn pieces *a* and *b* pass over and below respectively of the positionally fixed yarn pieces *a* and *b* (Figs. 3 and 11), this being due to the different depths of the slots 6, 7 on the one hand and the slots 9, 10 (Figs. 12, 13) on the other hand.

Due to the fact that the tie beaks 26, 27 have in the meantime changed their rotational position, the knot loops are now ready to be stripped off, and the yarn ends *c* and *d* are seized and held fast between respective cheek and jaw members 50, 51 of the respective tie beaks 26, 27. During the subsequent stripping off of the loops, the knot is completed and the surplus ends of yarn are cut off from the jaw members 51 and the cutting edges of 52. The stripping is effected by a motion of the tensioning member 17 which now moves axially and linearly between the two tie beaks to a protruding position in a direction to the left of beaks 26, 27, as viewed in Fig. 14. During this advancing motion the member 17 acts upon the yarn pieces *a* and *b* which is held between the slot 6 or 7, the yarn clamps 11, 12 and the tie beaks. Due to this action of member 17 the initially loose but completely looped individual knots are tightened and closed. The tie beaks now open and sever the ends *c*, *d* in conventional manner, as described, for example in German Patent 920,119. Thereafter the tension member 17 acts upon the yarn portions (Figs. 6 and 7) located between the tightened individual knots. Now the yarn pieces *a* and *b* can glide until their individual knots approach and touch each other (Fig. 8), thus forming the completed, knotted tie shown in Fig. 5.

The coaction of the individual operation described above is diagrammatically represented in the graph of Fig. 15 where the abscissa denotes units of time *t*, the

ordinate in the upper diagram portion denotes units of travel distance *d*, and the ordinate in the lower portion of the diagram denotes tensioning force *F*. The curve B indicates the travel motion of the tie beaks, the curve S the motion of the tension member 17, and the curve P the tension exerted by the member 17 upon the yarn.

The yarn pieces are placed in proper position during the time interval from *t*=0 to *t*=1. In the time interval from 1-5 there occurs the formation of the loops by means of the tie beaks as described above and known as such, for example from German Patent No. 920,119. This loop formation is terminated at *t*=5. Thereafter the tension member 17 moves beyond the tie beaks to such an extent that the yarn pieces are stripped off the tie beaks by forked arms 17a, 17b and are thereafter slightly pulled, although at this stage the yarn ends to be tied together are not yet placed under heightening tension. This stage is apparent from Fig. 6 and shown on larger scale in Fig. 9. Between the time interval points *t*=6 and *t*=7, the tie beaks are moved back for a short interval of time and are simultaneously opened so that the beaks are open at the time point 7 of the diagram (Fig. 7). In the meantime the tension member 17, at the time interval moment *t*=6, has reached its first step of motion when cam hump 30a (Fig. 14) reaches the cam follower 41 (at 130a in Fig. 15) and thus has tightened and closed the individual knots. Thereafter, after hump 30a passes the cam follower, the tension member 17 recedes a slight amount to the right (as viewed in Fig. 14) under the action of spring 31. The tension curve P in Fig. 15 indicates accordingly that the tension first increases and then declines between the time points 6 and 7, the decline in tension being terminated before time point 7 is reached. After the opening of the beaks, namely between time points 7 and 8, another forward motion is imparted to the tension member 17 by hump 30b of cam 30 reaching cam follower 41, and this motion, shown at 130b of curve S (Fig. 5), now imposes a tensioning stress upon the tie connection. As a result the two individual knots approach each other, gliding along the yarn piece embraced by the individual loop of each knot (Fig. 8). At time point 9 the motion of the tension member 17 is terminated and the tensioning force P reaches its maximum value, which then during the subsequent receding travel of the tension member again declines down to zero. The knotted tie is now completed and is also tested by means of the tension member 17. The yarn is released from the knotter and the weaving, coil winding or other fabricating operation can be continued.

While knotting devices according to the invention are applicable in connection with textile fabricating machinery of various types, such devices are particularly favorable for use with automatic coil winding machines in which the yarn pieces to be tied extend from opposite directions toward the knotter, for example, as shown and described in my U.S. Patent 2,733,870. By virtue of the loosening of the yarn pieces in the tie beaks prior to tensioning and tightening the connection, as afforded by the present invention, the occurrence of excessive stress in the yarn due to the knotting operation is prevented so that a repetition of the tying operation is unnecessary in the great majority of cases.

It should be understood, of course, that the foregoing disclosure relates to only a preferred embodiment of the invention and that it is intended to cover all changes and modifications of the examples of the invention herein chosen for the purposes of the disclosure, which do not constitute departures from the spirit and scope of the invention as set forth in the appended claims.

I claim:

1. A knotting device, particularly for forming a fisherman's knot, comprising a housing, a cup member having a hollow shaft rotatably journaled in said housing, first cam means operably connected for rotating said cup

member one revolution when said device is actuated for operation, a plurality of rotatably mounted beak members rotating in a first rotational direction and then clamping and subsequently releasing a respective one yarn end and forming therein an individual loop and knot passing around another yarn end, pinion means connecting said cup member with said beak members driving the latter in either direction, yarn tensioning means mounted for axial linear movement within said hollow shaft and operably movable relative to said beak members to strip said individual loops therefrom, second cam means operably joined in fixed timed relationship to said first cam means, and lever means operably connecting said second cam means with said tensioning means for actuating the axial movement of the latter relative to said beak members, said first and second cam means having respective related cam surfaces, said cam surfaces actuating said beak members to release the yarn ends after said individual loop forming but prior to actuation of said tensioning member to pull said individual loop knots together.

2. A knotting device, particularly for forming a fisherman's knot, comprising a housing, a cup member having a hollow shaft rotatably journaled in said housing, first cam means operably connected for rotating said cup member one revolution when said device is actuated for operation, a plurality of rotatably mounted beak members rotating in a first rotational direction and then clamping and subsequently releasing a respective one yarn end and forming therein an individual loop and knot passing around another yarn end, pinion means connecting said cup member with said beak members driving the latter in either direction, yarn tensioning means mounted for axial linear movement within said hollow shaft and operably movable relative to said beak members to strip said individual loops therefrom, second cam means operably joined in fixed timed relationship to said first cam means, lever means operably connecting said second cam means with said tensioning means for actuating the axial movement of the latter relative to said beak members, said first and second cam means having respective related cam surfaces, said cam surfaces actuating said beak members to perform a return rotational movement in opposition to said first rotational direction subsequent to said releasing of said yarn ends by said beak members.

3. A knotting device, particularly for forming a fisherman's knot, comprising a housing, a cup member having a hollow shaft rotatably journaled in said housing, first cam means operably connected for rotating said cup member one revolution when said device is actuated for operation, a plurality of rotatably mounted beak members each having respective cheek and jaw means rotating in a first rotational direction and then clamping and subsequently releasing a respective one yarn end and forming therein an individual loop and knot passing around another yarn end, pinion means connecting said cup member with said beak members driving the latter in either direction and for actuating said cheek and jaw means thereof, said cheek and jaw means including severing means for cutting off the protruding yarn ends, clamping means pivotally mounted outside of and engageable at one end thereof with said cup member wall, the other end of said clamping means being engageable with said yarn for clamping said yarn, yarn tensioning means mounted for axial linear movement within said hollow shaft and operably movable relative to said beak members to strip said individual loops therefrom, second cam means operably joined in fixed timed relationship to said first cam means, lever means operably connecting said second cam means with said tensioning means for actuating the axial movement of the latter relative to said beak members, said first and second cam means having respective related cam surfaces, said cam surfaces actuating said cheek and jaw means to sever the yarn ends

at least by the time said yarn tensioning member strips said individual loops from said beak members.

4. A knotting device according to claim 3 and including an eccentric cylindrical wall dispose around said cheek and jaw means of said beak members, said cylindrical wall being positioned in timed relationship relative to said cam surfaces so as to open said cheek and jaw means subsequent to the looping and closing of the individual knots by said beak members.

- 10 5. A knotting device, particularly for forming a fisherman's knot, comprising a housing, a cup member having a hollow shaft rotatably journaled in said housing, first cam means and cam follower means drivingly connected for rotating said cup member one revolution when said device is actuated for operation, a plurality of rotatably mounted beak members rotating in a first rotational direction and then clamping and subsequently releasing a respective one yarn end and forming therein an individual loop and knot passing around another yarn end, pinion means connecting said cup member with said beak members for driving the latter in either direction, yarn tensioning means mounted for axial linear movement within said hollow shaft and operably movable relative to said beak members to strip said individual loops therefrom, second cam means operably joined in fixed timed relationship to said first cam means, second cam follower means including lever means operably connecting said second cam means with said tensioning means for actuating the axial movement of the latter relative to said beak members, said second cam follower means having an adjustable member located in the force-transmitting path between said second cam means and said tensioning means for adjusting the force transmitted to said tensioning member from said second cam means.
- 15 30 35 6. A knotting device according to claim 5, said second cam follower means further including a resilient force-transmission member located in the force-transmitting path between said second cam means and said tensioning means.

- 40 7. A knotting device according to claim 5, the length of said tensioning member, its movement relative to said beak members and said cam surfaces of said first and second cam means being mutually positioned and dimensioned so as to linearly move said tensioning member relative to said beak members to first move the individual knots toward each other and subsequently to test the knotted tie by applying a predetermined tensile force thereto.

- 45 8. In a coil winding machine, a knotting device for forming a fisherman's knot in yarn ends, comprising a housing, a cup member having a hollow shaft rotatably journaled in said housing, first cam means and cam follower means drivingly connected for rotating said cup member one revolution when said device is actuated for operation, the outer peripheral wall of said cup member having a toothed gear portion formed therein and further having a plurality of first yarn-receiving slots of respectively different depths relative to the brim of said cup member, a plurality of rotatably mounted beak members each having respective cheek and jaw means rotating in a first rotational direction and then clamping and subsequently releasing a respective one yarn end and forming therein an individual loop and knot passing around another yarn end, pinion means in meshing engagement with said toothed gear portion of said cup and with said beak members for rotating and for actuating said cheek and jaw means thereof, a plurality of stationary clamping members fixed to said housing and concentrically mounted relative to said cup member, each of said stationary clamping members having other yarn-receiving slots of respectively different depths formed therein and positioned for cooperating with said first yarn-receiving slots to form a yarn-path through said cup member wall, movable clamping means comprising pivotable lever means and abutment means, said lever means being
- 50 55 60 65 70 75

7
pivotally mounted outside of and engageable at one end thereof with said cup member wall, the other end of said lever means being engageable with said abutment means for clamping said yarn, yarn tensioning means mounted for axial linear movement within said hollow shaft and operably movable relative to said beak members to pull said individual loops and knots mutually together and to strip said individual loops from said beak members, biasing means for normally urging said tensioning member in one predetermined direction, second cam means and second cam follower means operably joined in fixed timed relationship to said first cam means, lever means linking said second cam follower means with said tensioning means for actuating the axial movement of the latter relative to said beak members in opposition to said 15

one predetermined direction, said first and second cam means having respective related cam surfaces, said cam surfaces actuating said cheek and jaw means of said beak members to release the yarn ends after said individual loop forming but prior to actuation of said tensioning member to pull said individual loop knots together.
